EASEL TYPE LOOSE LEAF BINDER

Filed March 16, 1932

UNITED STATES PATENT OFFICE

CYRUS E. MOREHOUSE, OF CLIFTON HEIGHTS, PENNSYLVANIA

EASEL TYPE LOOSE LEAF BINDER

Application filed March 16, 1932. Serial No. 599,174.

My invention relates to a new and useful easel type of loose-leaf binder and it relates more particularly to a loose-leaf binder of a type adapted for use both as a loose-leaf book and also as an easel display stand for displaying the successive leaves of the book.

One of the objects of my invention is the provision of a loose-leaf binder of this character, which may be most effectively used for display purposes, with the greatest amount of clearance for each page as it is folded while the device is in the easel form.

With the above and other objects in view which will appear more fully from the following detailed description, my invention consists of a loose-leaf binder including a back, having spaced parallel hinge strips or plates of substantially rigid character, to each of which is hingedly secured a corresponding substantially rigid or stiff cover and to the outermost or free edge of one of the covers a base panel being also hingedly secured, so that when the book is opened into an easel, said base cover may form the base of a triangular easel.

My invention further consists of a pair of opposed parallel paper-clamp plates detachably secured to each other by means of suitable posts, and confining between them a stack of sheets;—one of said clamp plates being in turn hingedly secured to the hinged plates of the back of the book which carries the base panel, so that when the book is opened to its easel condition or form, the entire bound edges of the sheets may be swung out from between the hinged strips of the back of the book and clear of the back of the book.

My invention further consists of other novel features of construction which will appear more fully from the following detailed description.

Referring to the drawing in which like reference characters indicate like parts:

Figure 1 represents a perspective view of the book in the closed condition.

Figure 2 represents a perspective view of the book shown in the open condition as an easel.

Figure 3 represents an end view or edge

view of the book in the easel condition, shown partly in section on line 3—3 of Figure 2.

Figure 4 represents an end view of the book in the closed condition, with parts shown in section on line 4—4 of Figure 1. 55

Figure 5 represents a fragmentary sectional view, on a much enlarged scale on line 5—5 of Figure 1.

Figure 6 represents a fragmentary view of the hinge members of the book in the easel 60 condition, illustrating the effect on the relation between the bound edges and the hinged strips as the pages are folded back.

The loose-leaf book of my present invention includes a back 7 consisting generally of the top and bottom hinge strips or members 8 and 9 respectively, which are preferably stiff, rigid members covered on both sides with the outer and inner linings 10 and 11, which are then united at 12 to form a flexible connection between the top and bottom hinge strips 8 and 9. To the bottom hinge strip 9, a pair of similar hollow tubular and internally threaded screw-posts 13 are rigidly secured, at a right-angle thereto, by any suitable anchorages 14 embedded in said hinge strip 9 or extending therethrough and covered by the outer lining 10. A tubular spacer member 15 is placed over each of the hollow tubular screw posts 13, of a length corresponding to the desired spacing between the rigid or stiff hinge members or strips 8 and 9. Corresponding screws 16 are extended through the upper hinge strip or member 8 and threaded into the corresponding hollow tubular screw-posts 13, thereby to lock and secure the two hinge strips in fixed spaced relation to each other. 75 80 85

To the top and bottom hinge strips or members 8 and 9, corresponding stiff covers 18 and 19 are flexibly or hingedly secured, by means of the outer and inner linings 10 and 11 shown particularly in Figure 5, whereby said covers may be bent back upon or with respect to said hinge members 8 and 9 respectively, when it is desired to open the book for use as a book or for use as an easel. The lines of flexible or hinged connection are indicated at 20 and 21 respectively. 90 95 100

To the outer edge 22, of the bottom cover 19, a relatively stiff base panel 23 is flexibly connected, also preferably by means of the inner and outer linings 10 and 11, which are joined to each other for a suitable distance indicated at 24, which distance is sufficient to bridge the thickness of the book when closed as indicated particularly in Figure 4.

The total width of the flexible strip 24 formed

10 by the union of the inner and outer linings, and the width of the base panel 23 are sufficient to form an appropriate base for the triangular easel shown particularly in Figures 2 and 3. To the free or outer edge 25 15 of the base panel 23, a stiff flap or tab strip 26 is flexibly secured, also preferably by means of the inner and outer linings 10 and 11, which preferably extend the entire aggregate length of the successive series of flexibly 20 connected members 18, 8, 12, 9, 19, 24, 23 and 26. The flap or tab 26 is adapted to be folded up in overlapping relation to the lowermost or outer portion of the upper cover panel 18, when the latter is in the position shown in Figures 2 and 3. A pair of spaced snap-fastener sockets 27 are provided through the outermost portion of the cover 18, which are adapted to receive corresponding and registering snap-fastener studs 28 30 carried by the tab 26, when the device is set up as an easel, thereby detachably to secure said flap 26 to the cover member 18. When the device is closed in the form indicated in Figures 1, 4 and 5, the snap fastener sockets 35 27 receive another pair of registering snap fastener studs 29 which are secured to or carried by the base panel 23, thereby detachably to secure the upper cover 18 in a closed condition.

40 To the lower hinge strip or member 9, the hinge leaf 30 is fixedly secured, by rivets or otherwise, and the outer edge 31 carries a pintle 32 extending longitudinally.

The stack of sheets 33 are perforated with 45 two or more apertures, as at 34, for receiving binding posts.

A pair of opposed upper and lower binding plates or paper-clamping plates or bars 35 and 36 are provided, each being preferably 50 formed of a strip of sheet-metal, the longitudinal edges of which are bent in upon the strip so as to form a strip or bar of approximately double thickness.

The edge 37 of the lower bar 36 is cut away 55 at intervals, to enable it to serve as another hinge leaf, to coact with the hinge leaf 30. The pintle 32 is thus extended through the front and cut-away edge 37 of the bar 36, so that said bar is hingedly secured to the leaf 30, and hence to the lower hinge member or strip 9.

A pair of spaced tubular and internally threaded screw-posts 38 are rigidly secured to the lower bar 36, and at a right-angle 65 thereto, by any suitable anchorage such as the

flange 39 embedded or interposed between the two plies of the bar 36. A corresponding pair of registering telescope tubes 40 are similarly rigidly secured to the upper bar 35, by any suitable anchorage such as the flange 70 41 embedded in or interposed between the two plies or layers of the upper bar 35.

Screws 42 are then extended through the upper bar 35 and threaded into the tubular and internally threaded posts 38, thereby to 75 clamp the paper 33 between the upper and lower bars 35 and 36 respectively, as indicated in Figures 3, 4 and 5.

When the book is used as merely a loose-leaf book, the book is placed flat on the table 80 and the upper cover 18 is folded back about the flap folding line 20, and the base panel 23, carrying the tab strip 26, are also folded out in the opposite direction flat onto the table. The sheets or leaves 33 may then be 85 folded back one or more at a time in regular book fashion.

When the book is used for display purposes, the base panel 23 is bent back further and is joined to the cover 18 by means of the 90 tab 26, as indicated particularly in Figures 2 and 3. When in this condition, the bars 35 and 36 are swung out from between the hinge members 8 and 9 forming part of the back of the book, as indicated particularly in 95 Figures 2 and 3, this swinging action taking place about the pintle 32. As the successive leaves of the sheaf of pages 33 are folded backward, their weight and position operate on the bars 35 and 36 to swing them in a reverse direction, back into the space between the hinge members 8 and 9, thereby to tend to relieve the tension on the sheaf of pages 100 folded back and to permit a freer motion of folding of each leaf, and to expose more 105 freely to view the uncovered page of the front face of the easel, without any overhanging portion of the folded-back pages. By this means, the leaves or sheets 33 may be folded back with greater facility and the pages may 110 be exposed to view more completely.

I am aware that the invention may be embodied in other specific forms without departing from the spirit or essential attributes thereof and I therefore desire the present embodiment to be considered in all respects as illustrative and not restrictive, reference being had to the appended claims rather than to the foregoing description to indicate the scope of the invention. 115

Having thus described my invention, what I hereby claim as new and desire to secure by Letters Patent, is:

1. A loose-leaf book of the character stated, comprising a back including a pair of spaced 120 parallel hinge members, a cover flexibly connected to each of said hinge members, a base panel flexibly connected to the outer edge of one of said covers, and means for detachably fastening the free edge of said base panel to 125

the free edge of the other cover when the two covers are both folded back to form a generally triangular easel, a bar superimposed upon one of the hinge members, when the book is closed, having its outer edge hingedly secured to the outer edge of said hinge member, said bar carrying binding posts and a stack of loose-leaves carried upon said binding posts and detachably secured to said bar

10 by means of the same.

2. A loose-leaf book of the character stated, comprising a book including a pair of spaced and generally parallel hinge members, a corresponding cover flexibly connected to each of said hinge members, a base panel flexibly connected to the outer edge of one of said covers, and means for detachably fastening the free edge of said base panel to the free edge of the other cover, when the two

20 covers are both folded back to form a gener-

ally triangular easel, a bar superimposed upon the inner surface of one of the hinge members when the book is closed, said bar having its outer edge hingedly secured to the outer edge of said hinge member, said bar carrying binding posts and a clamping bar fastened to said binding posts, a stack of loose leaves carried upon said binding posts, and confined between said hinge bar and said clamping bar, said pair of bars and said binding posts and bound edges of the loose leaves therebetween, being all disposed between said pair of spaced and generally parallel hinge members, while the device is opened book-wise, and being disposed outside of said pair of spaced and generally parallel hinge members when the book is opened easel-wise.
